UNITED STATES PATENT OFFICE.

WILLIAM H. BECKER AND CHARLES W. STEED, OF ST. LOUIS, MISSOURI.

DISPENSING DEVICE FOR SODA-FOUNTAINS.

965,555.

Specification of Letters Patent. Patented July 26, 1910.

Application filed January 3, 1910. Serial No. 536,062.

To all whom it may concern:

Be it known that we, WILLIAM H. BECKER and CHARLES W. STEED, both citizens of the United States of America, residing in the city of St. Louis and State of Missouri, have invented certain new and useful Improvements in Dispensing Devices for Soda-Fountains, of which the following is a full, clear, and exact description, reference being had to the accompanying drawings, forming part of this specification.

Our invention relates to a dispensing device for soda fountains, the invention having for its object to provide a device of this description having a single spout and means for controlling the discharge through said spout of either a mixture of syrup and carbonated water, syrup alone, or carbonated water alone, thereby producing a dispensing device which, although of single type, has a multiple of functions.

Figure I is a top or plan view of our dispensing device with the top cap in horizontal section and the retaining screw above the operating lever omitted, the parts of the device being in the positions assumed when both of the cylinders are free to rotate in conjunction with each other. Fig. II is a similar view to Fig. I, with the parts in the positions assumed when the outer valve is held in a stationary position by the locking device provided for holding it. Fig. III is a perspective view of the locking bolt for holding the outer valve. Fig. IV is a vertical section through the dispensing device. Fig. V is a horizontal section taken on line V—V Fig. IV. Fig. VI is a vertical section through the lower end of the device with the port containing portion of the inner valve shown in elevation. Fig. VII is a fragmentary view of the outer shell showing a portion of the flavor indicator.

In the accompanying drawings:—1 designates the outer shell of our dispensing device which is provided at its upper end with a rim 2 and in the inner face of which are notches 3 adapted to receive a locking member to be hereinafter specifically referred to. 6 is a discharge spout detachably connected to the lower end of the shell 1, the connection between these members being preferably a screw threaded one, as seen in Fig. IV.

In the shell is a plurality of openings 4 that are adapted to receive syrup conducting pipes 7 that may lead from any desirable

source of supply of syrup. In the shell is also a plurality of ducts 5, all of which are arranged in communication with a header 8 attached to the shell, as seen most clearly in Figs. IV and V.

9 is a carbonated water conducting pipe leading to the header 8 and through which carbonated water may be conducted from any source of supply to be delivered into the header and pass therefrom through the ducts 5, the delivery of carbonated water from the ducts being controlled, however, by members within the shell 1, as will hereinafter appear. The pipes 7 and 9 are in-cased adjacent to the shell 1 within the housing 10 located between the shell and the chamber 11 from which the pipes extend.

12 is a cap loosely mounted on the shell 1 to turn thereon, the cap being provided with a depending flange that surrounds the rim 2 in the upper end of the shell.

13 designates an outer valve that is snugly fitted within the shell 1 and is adapted to be rotated therein. This valve is of plug type and chambered interiorly and in the wall of the valve is a duct 14 adapted to be placed in communication with either of the syrup conducting pipes 7 leading to the shell 1, and also a duct 15 adapted to be placed in communication with any one of the ducts 5 to which carbonated water is delivered from the header 8. The valve 13 has a screw threaded lower end that receives an adjusting or take up nut 16 which is adapted to bear against the lower end of the shell 1 when rotated upon the threaded lower end of the valve and whereby said valve is caused to be properly fitted within the shell. The valve 13 is provided with a top plate 17 secured to the body of the valve in any suitable manner and in which is a central aperture 18. The top plate 17 comprises a central member which is cut away at 19, an outer ring member 20 containing notches 21 and 22 located diametrically opposite each other, and stop members 23 interposed between the ring member and the central member. There is a circular channel 24 surrounding the central member and between it and the ring member except at the locations of the stop members 23.

26 designates an inner valve corresponding in shape to the shape of the outer valve 13 and located within said outer valve, but said inner valve being maintained with a proper fit within said outer valve by an ad-

justment or take-up nut 27 fitted to the lower end of the inner valve and bearing against the lower end of the outer valve. The inner valve has an imperforate upper 5 end 28 that is provided with a cylindrical stem 29 loosely seated in the central aperture 18 in the cap plate of the outer valve and having a non-circular head 30 that projects above said cap plate to receive a valve 10 actuating member to be more specifically mentioned. In the wall of the inner valve 26 is a duct 31 adapted to register with the duct 14 in the outer valve and a duct 32 adapted to register with the duct 15 in said 15 outer valve, the two ducts 31 and 32 being located in vertical alinement, with the object in view of providing under certain conditions to be hereinafter made plain for simultaneous delivery of syrup and carbonated water through the ducts 31 and 32 into 20 the chamber in the inner valve 26 to pass from said chamber and to discharge through the spout 6. The inner valve is also provided with a syrup conducting nozzle 33, 25 (see Figs. V and VI), extending from its wall to the center of the chamber in the inner valve, the duct in said nozzle being extended from a duct leading through the wall of the inner valve and which is adapted 30 to be placed in communication with the duct 14 in the outer valve at a time when the ducts 31 and 32 are not in communication with the ducts 14 and 15 in the outer valve, or with any syrup conducting pipe 35 7 or the carbonated water conducting pipe 9, at which the nozzle 33 is adapted to be placed in communication with any particular syrup conducting pipe 7 when the duct 14 therein is in registration with the duct 14 40 and said duct 14 is opposite to the pipe 7 from which it may be desired to occasion flow of syrup to said nozzle to be discharged from the lower end of the nozzle into and through the spout 6.

45 34 designates a hand lever by which the outer and inner valves 13 and 26 may be operated and which is provided with a handle 35 that projects outside of the shell and cap of the dispensing device. This 50 lever is arranged horizontally immediately above the top plate 17 of the outer valve and is provided with a slot 36 extending longitudinally thereof within which the non-circular head 30 of the stem 29 extending 55 from the inner valve is located. Provision is thereby made for rotation of the inner valve through the medium of the hand lever and also for longitudinal movement of the hand lever with an object in view 60 which will presently be made plain. The hand lever carries a lug 37 located at the front of the device and which is adapted to be moved into and out of the notch 21 in the ring member 20 of the outer valve top 65 plate 17. At the bottom of the hand lever

and near its rear end is a segmental shaped shifter 38 which is secured to the lever and is adapted to operate in the channel 24 in the outer valve top plate.

39 is a locking bolt resting upon the top 70 plate of the outer valve in the cavity produced by the channel 24 and the recess at 19. This locking bolt is operable in the notch 22 in the ring member 20 of the valve top plate and its rear end is arranged in a 75 pocket 17' in the central portion of the cap plate within which said rear end is always confined to provide for the locking bolt being guided when it is moved longitudinally. The locking bolt is provided with a notch 80 40 that receives the segment shaped shifter 38 through the medium of which the bolt is moved into and out of operative positions for service to be explained.

The hand lever 34 is provided with a 85 pointer 41 that is adapted to move around the external surface of the shell of the dispensing apparatus and which traverses an indicator 42 mounted upon the shell and which bears the names of the syrups or 90 flavors it may be desired to dispense from a soda fountain equipped with our dispensing device.

The operation of our dispensing device is as follows: One of the main objects in 95 view in this dispensing device is to provide for simultaneous flow into and through the dispensing device of both syrup or flavor liquid and carbonated water mixed in proper proportions with the result of guarding against the operator dispensing at one time too great an amount of either kind of liquid, and at another time too small an amount of either kind of liquid. With this in view, the valves 13 and 26 are adapted to 100 be so adjusted that there may occur simultaneous flow into the chamber in the inner valve 26 through the ducts 31 and 32 when placed in communication through the ducts 14 and 15 in the outer valve with a syrup 110 conducting pipe 7 and a duct 5 leading from the header 8 with which the carbonated water conducting pipe 9 communicates. To so adjust said valves, the hand lever 34 is operated as follows: It will be assumed first 115 that the hand lever and its carried parts are in the positions illustrated in Figs. I and IV, at which time the locking bolt 39 is withdrawn from any notch 3 at the upper end of the shell 1, and the lug 37 at the bottom of the hand lever is positioned in the notch 21. The operator now moves the hand lever to 120 impart rotation to both of the valves 13 and 26 until the pointer 41 is brought to a position to indicate upon the indicator 42 the flavor it is desired to dispense through the dispensing device, and at which time the duct 14 will be in alinement with the syrup conducting pipe 7 through which said flavor 125 is conducted. The duct 14 in the outer valve 130

will also at this time be in communication through one of the ducts 5 with the header 8 from which carbonated water is supplied. There is no communication established at 5 this time through the inner valve by reason of the fact that the ducts 31 and 32 therein are out of registration with the ducts 14 and 15, but such communication is established following the next operation which 10 involves a shifting of the hand lever 34 to prevent rotation of the outer valve so that the registration of the ducts 14 and 15 with the pipe 7 and the duct 5 may be retained, and the inner valve be rotated independently of the outer valve. In performing the 15 action just referred to, the operator first moves the hand lever longitudinally in a backward direction whereby the locking bolt operating member 38 carried by the hand lever is caused to move the locking bolt longitudinally to set it in one of the notches 3 and provide for its exerting a holding action upon the outer valve. The inner valve is then rotated by turning the hand lever, 20 while the outer valve remains stationary until the ducts 31 and 32 in the inner valve are brought into registration with the ducts 14 and 15 in the outer valve and simultaneous flow of liquid from the pipe 7 and the 25 header 8 into the chamber of the inner valve is established, this registration being maintained until the desired quantity of liquids to be dispensed has entered into the chamber of the inner valve and been discharged therefrom through the spout 6 into the vessel held 30 to receive it. The discontinuance of flow of liquids is occasioned by only a slight movement of the inner valve to carry the ducts 31 and 32 out of registration with the 35 ducts 14 and 15. It is to be noted that the movement of the inner valve independently of the outer valve is permissible due to the displacement of the lug 37 carried by the hand lever from the notch 21 in the top 40 plate of the outer valve so that said lug may move in an arc of a circle in the channel 25. It is desired in some instances to dispense syrup without dispensing carbonated water therewith and it is for this reason that we 45 provide a nozzle 33 carried by the inner valve and arranged aside from the ducts 31 and 32. There is no duct in the inner valve registerable with said nozzle through which carbonated water may be discharged when 50 syrup is discharged through said nozzle and, as a consequence, when the duct 14 in the outer valve is brought into registration with the syrup conducting pipe and the duct in the nozzle 33 is thereafter brought into registration with said duct 14, there will be a 55 discharge of syrup only from the dispensing device through its spout 6.

We claim:—

1. In a dispensing device, a shell having 60 a passageway therethrough, an outer valve

within said shell provided with a duct, an inner valve within said outer valve provided with a duct, and means for operating said valves consecutively to first place the duct in the outer valve in communication with the passageway in said shell then lock said outer valve and thereafter place the duct in the inner valve in communication with said passageway in the shell and the duct in the outer valve. 70

2. In a dispensing device, a shell having a passageway therethrough, an outer valve within said shell provided with a duct, an inner valve within said outer valve provided with a duct, means for locking said outer valve in a set position after it has been moved to place the duct therein in communication with the passageway in the shell, and means for operating said valves whereby the duct in said outer valve is first 80 placed in communication with the passageway in the shell, and whereby the duct in the inner valve is thereafter placed in communication with the duct in the outer valve and with the passageway in the shell. 85

3. In a dispensing device, a shell having a passageway therethrough, an outer valve within said shell provided with a duct, an inner valve within said outer valve provided with a duct, and a lever shiftably 90 fitted to one of said valves and movable into engagement with the other valve, whereby said valves may be operated consecutively to first place the duct in the outer valve in communication with the passageway in said shell, and thereafter place the duct in the inner valve in communication with the duct in the outer valve. 100

4. In a dispensing device, a shell having a passageway therethrough, an outer valve 105 within said shell provided with a duct, an inner valve within said outer valve provided with a duct, a lever shiftably fitted to one of said valves and movable into engagement with the other valve, whereby 110 said valves may be connected and operated consecutively to first place the duct in the outer valve in communication with the passageway in said shell, and thereafter place the duct in the inner valve in communication 115 with the passageway in the shell and the duct in the outer valve, and means operable by said lever whereby said outer valve may be held from movement during the movement of said inner valve to place 120 the duct therein in communication with the duct in the outer valve.

5. In a dispensing device, a shell having a passageway therethrough, an outer valve within said shell provided with a duct, an 125 inner valve within said outer valve provided with a duct, a lever shiftably fitted to one of said valves and movable into engagement with the other valve, whereby said valves may be connected and operated 130

- 4
- consecutively to first place the duct in the outer valve in communication with the passageway in said shell, and thereafter place the duct in the inner valve in communication with the passageway in the shell and the duct in the outer valve, and a locking bolt operable by said lever adapted to engage said shell to hold said outer valve from movement during the movement of 5 said inner valve to place the duct therein in communication with the duct in said outer valve.
6. In a dispensing device, a shell having a passageway therethrough, an outer valve 10 within said shell provided with a duct, an inner valve within said outer valve provided with a duct, an operating lever slidably fitted to said inner valve and adapted to be moved into and out of engagement 15 with said outer valve, and means operable by said lever whereby said outer valve may be held in a set position while said lever is being operated to move said inner valve.
7. In a dispensing device, a shell having 20 a passageway therethrough, an outer valve within said shell provided with a duct, an inner valve within said outer valve provided with a duct, an operating lever slidably fitted to said inner valve and adapted to be moved 25 into and out of engagement with said outer valve, and a locking bolt operable by said lever whereby said outer valve may be held in a set position while said lever is being operated to move said inner valve.
8. In a dispensing device, a shell having a 30 passageway therethrough, an outer valve within said shell provided with a duct adapted to register with the passageway in the shell, an inner valve within said outer valve provided with a duct adapted to register with the duct in the outer valve, an operating lever slidably fitted to said inner valve and having a member slidably fitted to said outer valve, a locking bolt carried 35 by said outer valve adapted to engage said shell, and a member carried by said lever whereby said bolt may be shifted to place it in engagement with said shell and withdraw it from such engagement.
9. In a dispensing device, a shell having a 40 passageway, an outer valve within said shell provided with a duct adapted to register with said passageway, an inner valve within said outer valve having a duct adapted to register with the duct in the outer 45 valve.

valve, means for connecting said valves, and means for operating said connecting means.

10. In a dispensing device, a shell having two passageways therethrough in different planes, an outer valve within said shell provided with ducts adapted to register with said passageways in the shell, an inner valve within the outer valve provided with two ducts for registration with the ducts in the outer valve, means for operating said outer and inner valves to place the ducts therein in communication with the passageways in said shell whereby the ducts in the outer valves are first brought into such communication and the ducts in the inner valve are 50 thereafter brought into such communication, and means for locking said outer valve from movement while the inner valve is being moved.

11. In a dispensing device, a shell having two passageways therethrough in different planes, an outer valve within said shell provided with a duct adapted to register with said passageways in the shell, an inner valve provided with a duct, means for connecting said valves and means for operating said connecting means whereby the duct in the outer valve is first brought into communication with the duct in the shell and the duct in the inner valve is thereafter brought 80 into communication with said passageway in the shell.

12. In a dispensing device, a shell having two passageways therethrough in different planes, an outer valve within said shell provided with a duct adapted to register with said passageways in the shell, an inner valve provided with a duct, means for operating said valves whereby the duct in the outer valve is first brought into communication 90 with the duct in the shell and the duct in the inner valve is thereafter brought into communication with said passageway in the shell, and means whereby said outer valve is locked from movement during movement 95 of said inner valve.

In testimony whereof, we have hereunto affixed our signatures, this 30th day of December, 1909.

WILLIAM H. BECKER.
